Patented Nov. 25, 1919.

2 SHEETS—SHEET 1.

Fig. 1.

Distillation of petroleum and anhydrous aluminum chloride, with specified regulation of fires, the anhydrous aluminum chloride being in solution in (combination with) a part of the oil operated upon. Continuation of distillation approximately at least to the lowest point at which the residual material is sufficiently fluid for substantially the whole of it to be withdrawn after the manner of a liquid. Arrest of distillation while the residual material has a substantial content of liquid hydrocarbons.

Fig. 3.

Distillation of petroleum and anhydrous aluminum chloride, with specified regulation of fires, the anhydrous aluminum chloride being in solution in (combination with) a part of the oil operated upon. Continuation of distillation approximately at least to the lowest point at which the residual material can be freed from aluminum by boiling with water. Arrest of distillation while the residual material is in condition to allow its carbonaceous content and the main part at least of its aluminum chloride content to be separated from each other by washing with water.

Arrest of distillation while the residual material has a substantial content of liquid hydrocarbons.

UNITED STATES PATENT OFFICE.

ERNEST B. COBB, OF JERSEY CITY, NEW JERSEY, ASSIGNOR TO STANDARD OIL COMPANY, OF BAYONNE, NEW JERSEY, A CORPORATION OF NEW JERSEY.

MAKING LOW-BOILING OIL FROM HIGHER-BOILING PETROLEUM OR RELATED OIL.

1,322,762.

Specification of Letters Patent. Patented Nov. 25, 1919.

Continuation of application Serial No. 834,844, filed April 25, 1914. This application filed October 4, 1919. Serial No. 398,578.

To all whom it may concern:

Be it known that I, ERNEST B. COBB, a citizen of the United States, residing at Jersey City, in the county of Hudson and State of New Jersey, have invented certain new and useful Improvements in Making Low-Boiling Oil from Higher-Boiling Petroleum or Related Oil, of which the following is a specification.

This invention relates to obtaining oils which are composed mainly at least of hydrocarbons with boiling points normal to naphtha and the lighter end of burning oil (kerosene) (say up to 302° F. for naphtha and 302° F. to 450° F. for the lighter end of burning oil, the boiling points regarded herein as normal to the heavier end of burning oil being from 450° F. to 572° F.) by operating upon petroleum in forms (distillate and undistilled) which contain a large proportion at least of higher boiling hydrocarbons (say hydrocarbons with boiling points above 450° F.) and particularly, but not exclusively, distillate oils of this description which are mainly at least composed of hydrocarbons with viscosities too low for normal constituents of other than light grades of lubricants (say with viscosities under one hundred and seventy seconds at 100° F. with an Engler viscosimeter with which water exhibits a viscosity of fifty three seconds at 60° F.), such as the inferior grades of burning oil (kerosene) (either finished or untreated) and the oils commonly disposed of as gas oil or fuel oil on account of their being unfit on the one hand for burning oil (kerosene) and on the other for medium and heavy lubricants; for which products there is usually a good demand at higher prices than those of gas oil or fuel oil.

In accordance with the present improvements, the petroleum is distilled with anhydrous aluminum chlorid (Al_2Cl_6) in solution in (combination with) a part of the oil operated upon (useful proportions hereinafter indicated) at temperatures sufficient to split up component hydrocarbons of the oil; and the said distillation, after continuance for such appropriate period as may be preferred, is arrested while the residual material is in condition for its carbonaceous content and the main part at least of its aluminum chlorid content to be separated from each other by washing with water.

This separation will be possible as long

as the residual material is liquid in whole or in part (or, in other words, as long as it has a substantial content of liquid hydrocarbons); and it may be effected even after the residual material has attained an at least approximately dry condition; but it is liable to be defeated by carrying the distillation too far, with consequent overheating of the residual material.

By terminating the distillation at the lowest point at which the residual material is sufficiently liquid for substantially the whole of it to be pumped out or otherwise withdrawn from the still through a pipe connection or the like, that is to say, after the manner of a liquid, practically the maximum service will have been obtained from the anhydrous aluminum chlorid employed consistently with the minimum of work in cleaning out the still. By continuing the distillation beyond this point, more work must be expended in cleaning the still; but greater service will have been obtained from the anhydrous aluminum chlorid employed. By stopping when the residual material attains the lowest point at which it can be freed wholly from the element aluminum (traces only excepted) by boiling with water, practically the maximum service will have been obtained from the aluminum chlorid employed consistently with a complete recovery of the aluminum chlorid content of the residual material by washing with water; but the service obtainable from the anhydrous aluminum chlorid is not necessarily exhausted even then.

Further, in accordance with the present improvements, when the desired distillation has been completed, the whole, or any appropriate part, of the then existing residual material is washed with water in such manner that the washing water is applied to material which contains a large part at least of the aluminum chlorid content of the said residual material.

Thus if the distillation should be arrested while the residual material is in condition for a separation to be effected between its liquid hydrocarbons (some of them at least) and the remainder of said residual material by settling and decantation (or in any other way which does not involve a washing with water), such a separation can be effected in any known or suitable way; and the remainder of the residual material (contain-

ing all, or nearly all, the aluminum chlorid) can then be washed with water; but it is not necessary in any case to separate liquid hydrocarbons from other matter composing the residual material prior to washing with water; since the washing water can be applied to the undivided residual material, whatever may be its condition with respect to the presence therein (or absence therefrom) of liquid hydrocarbons.

One effect of the washing with water is to separate the aluminum chlorid and the carbonaceous content of the washed material from each other, the aluminum chlorid being obtained in aqueous solution. Liquid hydrocarbons (if any) contained in the washed material will also be separated from the remaining carbonaceous matter (if any).

Another feature forming part of the present improvements consists in subjecting all or any desired part of the liquid hydrocarbons which may be recovered from the aforesaid residual material to distillation with a fresh supply of anhydrous aluminum chlorid.

By thus recovering all the liquid hydrocarbons from said residual material and distilling them with anhydrous aluminum chlorid, practically the entire carbon content of the oil originally operated upon (excluding loss) can be obtained either in the form of distillate from distilling in the presence of anhydrous aluminum chlorid or else in the form of coke, without continuing the distillation with anhydrous aluminum chlorid so far in any run as to leave the residual material without a substantial content of liquid hydrocarbons at the close of the run.

Most advantageously oil composed at least in part of recovered hydrocarbons would be distilled (say to dryness, or to a lesser extent, if preferred); and the resulting distillate would then be distilled with the new supply of anhydrous aluminum chlorid; but (if preferred) the recovered hydrocarbons can be distilled with a new supply of anhydrous aluminum chlorid without undergoing this intermediate distillation.

The recovered oil can be disposed of otherwise, in whole or in part, as may be preferred, in case it should not be desired to distil it with a new supply of anhydrous aluminum chlorid; and the residual material likewise can be disposed of otherwise, in whole or in part, as may be preferred, in case it should not be desired to wash the same (in whole or in part) with water.

Where liquid hydrocarbons are recovered by a separation without washing with water, they can be distilled with a fresh supply of anhydrous aluminum chlorid or be otherwise disposed of (in whole or in part) without reference to what may be done with the

remainder of the residual material; and conversely the remaining residual material can be disposed of as may be preferred, without reference to what may be done with oil recovered from the residual material without washing with water.

The products of the distillation with anhydrous aluminum chlorid are fractionated to obtain oils of such grades as may be desired and obtainable.

Figures 1, 2 and 3 are diagrams, which are believed to be self explanatory, and which illustrate certain typical procedures; and Figs. 4, 5 and 6 are diagrams of apparatus appropriate to be used in distilling petroleum with anhydrous aluminum chlorid. The illustrations are not intended to be exclusive; neither is the invention restricted to the examples hereinafter set forth, or to the details of such examples.

For effecting the distillation with anhydrous aluminum chlorid, an ordinary still and an ordinary water cooled condenser connected with said still by a vapor pipe will answer. In Fig. 4 the still *a* is shown as being of ordinary horizontal cylindrical form and as having manholes *b*, a valved charging line *c* for supplying petroleum to the still, and a valved discharge line *d* for withdrawing the residual material (in whole or in part) after the manner of a liquid, when the same is sufficiently fluid to be so withdrawn; and the water cooled condenser *e* is connected with the still *a* by the vapor pipe *f*. The distillate flows into the receiver *g*; and the uncondensed vapors and the gases pass, by the pipe *h*, to waste, or to such place of utilization as may be preferred.

A still, which would hold say six hundred barrels of forty gallons each when full, may well receive a charge of about four hundred barrels of the gas oil or fuel oil mentioned, and a limited proportion, not more than about ten per cent. by weight, of anhydrous aluminum chlorid. The temperature is gradually raised until distillate commences to flow from the condenser outlet (which may be in say six or eight hours or thereabout from the commencement of firing); and the fires are regulated to give a good flow (say fifteen to twenty barrels an hour or thereabout) of distillate.

Distillation is best conducted in this way to the end, or at least approximately to the end, of the run, the temperature of the oil increasing gradually with the progress of the distillation. The run is terminated sooner or later, as hereinabove explained.

In practice, in order to terminate runs with practical uniformity at such point as may previously have been determined upon, it would be ascertained by test runs that the proper point had been reached when a certain percentage of distillate had been

received; and distillation would be stopped in the different runs when such standard percentage of distillate had been received.

A sufficient test for ascertaining when the distillation has been carried approximately at least to the lowest point at which the residual material can be freed wholly from aluminum (traces only excepted) by boiling with water is to secure samples of the residual material at different periods, to boil each sample in water for say ten minutes and to subject the undissolved remainder of the same to any known or suitable test for ascertaining the quantity of the element aluminum (if any) therein. When the undissolved remainder of any sample is the first to exhibit more than traces of said element, it will be known that the residual material at the time of taking the sample had attained (or had perhaps overpassed somewhat) the lowest point at which it could be freed wholly from aluminum by boiling with water (traces only excepted).

At the close of the run, the heating is discontinued; and later, when the running (if any) from the condenser outlet has ceased, the residual material is removed from the still preparatory to charging the still for a new run. If the said residual material is sufficiently fluid (or to the extent to which it may be sufficiently fluid) the same is advantageously withdrawn after the manner of a liquid.

Assuming that it should not be preferred to operate upon or to dispose of the residual material (in whole or in part) in some other way, the same would be washed with water of appropriate temperature, say at or above 150° F.; so as to separate the carbonaceous content of said residual material and the main part at least of its aluminum chlorid content from each other, the aluminum chlorid being obtained as a solution in water and the carbonaceous matter either as liquid hydrocarbons, or partly as liquid hydrocarbons and partly as soft coke, or as soft coke, according to the extent to which distillation has been carried.

It is desirable to use as little water as will suffice to unite with the aluminum chlorid. An amount equal to twenty five per cent. by volume of the material to which the washing water is applied will suffice; and a smaller amount may do so, especially if the washing be conducted in a systematic manner by transferring the washing water from a previously partly washed body of residual material to residual material which has not been washed to the same extent, if at all.

Liquid hydrocarbons (if any) forming part of the washed material will float on the aqueous aluminum chlorid solution and can be readily separated from the latter, say by settling and decantation for example. The aqueous solution of aluminum chlorid and

the non-liquid carbonaceous matter (if any) of the residual can also be readily separated from each other.

Oil composed at least in part of so recovered hydrocarbons (if obtained in substantial proportions) would be distilled to dryness, or to a lesser extent if preferred; and the distillate (separated from whatever water, if any, may pass over) would be distilled with a fresh supply of anhydrous aluminum chlorid, it may be by itself, but better in admixture with other oil.

The aqueous aluminum chlorid solution and the coke (if any) derived from the residual material of the distillation with anhydrous aluminum chlorid as aforesaid would be disposed of as might be preferred; as would be also the coke (or other residual material) obtained in distilling liquid hydrocarbons (if any) recovered from the said residual material of the distillation with anhydrous aluminum chlorid.

By evaporation of the aluminum chlorid solution to dryness, alumina can be obtained as residue; while hydrochloric acid would pass off with the water vapor.

Alumina and hydrochloric acid (the latter in vapor form) can also be obtained by combustion of residual material from any distillation with anhydrous aluminum chlorid (with or without prior separation of its liquid hydrocarbons, if any, therefrom); if it should be preferred thus to burn said residual material rather than to wash it with water as aforesaid.

From alumina and hydrochloric acid, in whatever way they may be obtained, anhydrous aluminum chlorid can be reconstituted by known methods. For example, anhydrous aluminum chlorid distils over when dry chlorin (which is obtainable by known means from hydrochloric acid) is passed over an incandescent mixture of coke and alumina.

Returning now to the distillation of petroleum with anhydrous aluminum chlorid, it suffices to collect the distillate all in one receiver, whatever may be the form of petroleum operated upon. Any solution of anhydrous aluminum chlorid which may come over with distillate is allowed to settle out and is separated for future use. The condenser, and a liquid separator intermediate the condenser and the distillate receiver, may well be elevated above the still; and the bottom of the separator be connected with the still by a suitably trapped pipe for conducting the aluminum chlorid solution back to the oil in distillation; while the upper part of the separator would be connected with the distillate receiver for conduct of the distillate thereto. In Fig. 5 the condenser *e* is shown as thus elevated; a liquid separator *i* is shown between said condenser *e* and the distillate receiver *g*; a trapped pipe

j connects the bottom of the separator with the still for returning thereto any solution of aluminum chlorid which may pass over; the trap being formed as shown by the upward bend of the pipe *j* on leaving the separator *i*; and a pipe *k* connects the upper part of the said separator with the receiver *g* for delivering distillate to the latter.

The distillate may be washed with water and then fractionated with partial or with complete distillation by means of dry heat; or the fractionation may be performed by partial distillation in a steam still, in which case the water of condensation serves to wash the distillate. Washing the distillate with water can precede the steam distilling, if preferred; and the residual oil from partial distillation with dry heat or in the steam still can be fractionated by dry heat, or can be disposed of otherwise, as may be preferred. In some cases at least it may be best to agitate the washed distillate with sufficient alkali (caustic soda lye) to neutralize any remaining acid (hydrochloric acid) therein before fractionating by distillation. In fractionation cuts are made to obtain oils of the desired grades, all of which may well be composed at least mainly of hydrocarbons with boiling points not exceeding 450° F. and also to obtain, if desired, higher boiling oils. The low boiling oils, say various grades of naphtha, may be finished for use or sale by giving them the customary treatment with sulfuric acid and alkali; and the burning oil (kerosene) distillate can be similarly finished. The higher boiling oils, as a whole or in such part as may be preferred, can be distilled anew with anhydrous aluminum chlorid; or they can be disposed of otherwise, as may be preferred.

Good results have been obtained in a small way with an amount of anhydrous aluminum chlorid equal to about seven per cent. by weight of the oil operated upon; nine per cent. by weight would probably give better results. The proportion can be varied within wide limits. Reduction of the proportion of anhydrous aluminum chlorid tends to lower the yield of hydrocarbons with boiling points below 450° F. Increase in the proportion of anhydrous aluminum chlorid tends to increase the proportion of such hydrocarbons; but it will probably not be worth while to exceed about ten per cent. by weight in any case. If this percentage be added to petroleum distillate (gas oil or fuel oil or other distillate) the anhydrous aluminum chlorid dissolves at appropriately elevated temperature in a part of such distillate; and the solution will form a distinct layer underneath the remainder of the distillate if not kept in suspension therein by agitation. The anhydrous aluminum chlorid can be added to the oil in the still in solid state or in solu-

tion; or it can be placed in the still before charging the same with oil. When the still is heated the aluminum chlorid dissolves gradually in a part of the oil when the temperature suffices. Probably if enough aluminum chlorid were employed, the whole of the oil might form a solution thereof; but it is not believed that so large a proportion would be desirable, if practicable.

From gas oil or fuel containing some 75 paraffin wax and of a gravity of 33.8° B., which comprised over ninety per cent. by volume of hydrocarbons with boiling points above 450° F. and which, if distilled in the usual way in a laboratory flask, would give 80 first runnings equal to five per cent. by volume with a gravity of 48° B., an amount of naphtha (distilling over up to 302° F.) of 67° B. equal to about twenty and a half per cent. by volume of said gas oil or fuel 85 oil and water white burning oil (kerosene) of 45.6° B. equal to twenty nine per cent. by volume of said gas oil or fuel oil have been obtained, using about 7% by weight of anhydrous aluminum chlorid and working 90 a small way. These oils comprised the naphtha wholly and the kerosene mainly of hydrocarbons with boiling points not exceeding 450° F. The first 5% runnings of the distillate had a gravity of 80.7° B. The 95 naphtha hydrocarbons have been found to be mainly at least of a saturated character, exhibiting small heating effect, as compared with naphtha produced in the ordinary cracking of crude petroleum, when shaken 100 up with sulfuric acid of 66° B. If it should be desired to collect an oil consisting wholly of hydrocarbons having boiling points up to 350° F. (useful as fuel in gasoline explosive engines) the yield might be between five and 105 ten per cent. by volume more than that of the naphtha mentioned.

From a finished burning oil (kerosene) obtained from crude petroleum of California free from paraffin wax and having 110 a gravity of 40.3° B., which comprised over thirty per cent. of hydrocarbons with boiling points above 450° F., and which, if distilled in the usual way in a laboratory flask, would give first runnings equal to five 115 per cent. by volume having a gravity of 51.9° B. there has been obtained (using about 7% by weight of anhydrous aluminum chlorid and working in a small way) a yield of nearly twenty seven per cent. by 120 volume of naphtha of 57.7° B. gravity, composed wholly of hydrocarbons with boiling points up to 302° F. (first runnings equal to five per cent. by volume having a gravity of 71° B.) and about sixty per cent. of burning oil (kerosene) distillate over ninety-five per cent. of whose hydrocarbons had boiling points not exceeding 450° F.

From finished burning oil (kerosene) of low grade and about 45.3° B. gravity ob- 125

tained mostly from Pennsylvania and Lima crude petroleum (in part from each), using about 7% by weight of aluminum chloride and working in a small way, about 24.5% by 5 volume of naphtha of 68.7° B. distilling over up to 302° F. first 5% runnings 81.7° B.) was obtained and over 61.5% by volume of burning oil (kerosene) distillate, more than eighty five per cent. of whose 10 hydrocarbons had boiling points not exceeding 450° F. The oil operated upon contained some paraffin wax; it consisted more than fifty per cent. by volume of hydrocarbons with boiling points above 450° F.; 15 and the first 5% runnings had a gravity of 60.3° B.

The temperatures of the oil in distillation and other things will vary considerably, according to the character of the starting material and other circumstances. In a small 20 scale test run (which was made by way of example subsequently to the filing of my application of April 25, 1914, officially numbered 834,344, of which the application for 25 the present patent is a continuation, in order to illustrate a particular case in detail and in which a charge of 2,500 cubic centimeters of a gas oil of 34.4° B. gravity was distilled with anhydrous aluminum chloride to dryness) the oil in distillation showed a temperature of 315° F. when distillate commenced to flow from the condenser outlet (about an hour and twenty-five minutes after commencement of firing) and a temperature of 30 nearly 700° F. when less than one per cent. of obtainable distillate remained in the still (about eleven hours and forty five minutes later). The observed temperature of the vapors passing over to be condensed as distillate was 200° F. when distillate commenced to flow from the condenser outlet and 470° F. when the oil had been distilled to the above mentioned state of approximate dryness. In this test run one hundred and 45 fifty grams of anhydrous aluminum chloride (equal to seven per cent. by weight of the original still charge) were employed, the whole being introduced at the start. The distillate was collected in sixteen fractions, 50 each equal to five per cent. by volume of the original still charge, and a final fraction of 72/100 of one per cent. The residue (coke and aluminum chloride) left in the still weighed 389 grams. Some of the aluminum 55 chloride passed over with the vapors which were condensed as distillate. The first of the following tables (Table A) shows the gravities of the several fractions, the respective temperatures of the oil in distillation 60 and the vapors passing over to be condensed as distillate at the close of each collection, and the time occupied in each collection. The second table (Table B) gives the results of assays of the several 5% fractions of 65 distillate and shows the percentages of each

fraction with boiling points up to 302° F., 350° F., 450° F. and 572° F., respectively. This table also shows (1) the final temperature of the vapors in the flask neck in each assay in which such final temperature was 70 below 572° F., (2) the percentage of oil remaining in the flask at the close of the assay in each case in which the vapors in the flask neck attained a temperature of 572° F., and 75 (3) the percentage of loss in each assay. 75

An assay of a specimen of the gas oil charged (34.4° B. gravity) showed the following percentages:

Boiling points up to 302° F.....	1.5%	115
Boiling points 302° F. to 350° F.....	2.0%	
Boiling points 350° F. to 450° F.....	3.5%	
Boiling points 450° F. to 572° F.....	13.5%	
Residual oil in flask at 572° F.....	86.0%	
Loss.....	0.5%	120

Instead of operating upon distillate, use may be made of petroleum in undistilled forms, as crude petroleum, or residues from reduction (partial distillation) of crude petroleum with or without injection of 125 superheated steam into the oil; but it is considered less advantageous to operate upon undistilled petroleum than upon distillates on account of the larger proportion of carbon in the former. 130

Gas oil yields more carbon than burning oil (kerosene). A considerable amount of gas and light vapors, which would escape condensation in the ordinary water cooled condenser, are likely to be formed in any case.

Distillates of higher boiling hydrocarbons than those of the gas oil or fuel oil mentioned (such as heavy paraffin distillate or 10 pressed paraffin distillate, or even residue from partially distilling pressed distillate) can be operated upon; but it is considered that to do so would be less advantageous than to operate on gas oil or fuel oil, or 15 low grade burning oil (kerosene) (finished oil or untreated distillate). The distillates obtained in reducing pressed paraffin distillate can be operated upon; and, in fact, the lighter portion of such distillate (when 20 available) commonly forms part of the gas oil or fuel oil mentioned. So-called acid oil, obtained in known ways from acid sludge from treating burning oil (kerosene) distillate and lubricant stock (one or other, or 25 both) with sulfuric acid (usually acid of 66° B., sometimes stronger) can be operated upon alone or in mixtures. Hydrocarbon oils which are not forms of petroleum, but have a suitably close relation 30 thereto, such as shale oils and the like, can be operated upon.

The fractionation of the distillate from the distillation with anhydrous aluminum chlorid, instead of being performed wholly 35 in a distinct distillation, may be performed at least in part in the distillation with anhydrous aluminum chlorid by means of a partial condensation or a series of partial condensations of the vapors. Condensate, 40 or one or more condensates, from such partial condensation or condensations can be returned to the oil in distillation; or can be collected as distillate, as may be preferred. The partial condensers (one or more) may 45 be air cooled or liquid cooled. They may receive the vapors at or near the bottom, so that these pass in opposite directions in contact with retrograding condensate; or they may receive the vapors at or near the top, 50 so that the vapors, as well as the condensate, travel downward.

In Fig. 6 a partial condenser *l* is shown between the still *a* and the water cooled condenser *e*; and the condensate, which 55 forms therein, can either be returned to the still *a* through the valved pipe *m*, or be delivered through the valved pipe *n* and cooling coil *p* to the distillate receiver *q*.

The distillation with anhydrous aluminum chlorid is not necessarily performed by charging a still and then running off the charge. It may be performed in a more or less continuous manner. Oil might be supplied to the charge in the still while the 65 distillation is going on, with or without ad-

dition thereto of anhydrous aluminum chlorid, and with or without the withdrawal of residual material, during the run. Continuous stills of any known or suitable form can be used.

Distillate from the distillation with anhydrous aluminum chlorid can be treated with sulfuric acid and alkali prior to fractionation by further distillation; but it is considered better to apply such treatment to 70 fully fractionated oils.

Other materials not inconsistent with the action of the aluminum chlorid on hydrocarbons can, of course, be used in addition thereto. Anhydrous perchlorid of iron 80 (Fe_2Cl_6), if used in addition to the anhydrous aluminum chlorid, is believed to combine with the latter and so to form a double chlorid of iron and aluminum; which acts similarly to the aluminum 85 chlorid; although a difference in reaction has been observed; and probably a number of other substances would act similarly. In naming aluminum chlorid, therefore, in the hereinafter written claims it will be 90 understood that double chlorid of iron and aluminum and other similarly acting substances are intended to be included and not excluded by such recital.

Similarly, in naming petroleum in the 95 claims, other related oil, such as shale oil or the like, is intended to be included and not excluded by such recital.

In stating in said claims that the petroleum is to be "in any appropriate form," it 100 is to be understood that gas oil or fuel oil, burning oil (kerosene) or other like form is primarily, but not necessarily exclusively, intended.

In stating therein that the petroleum is 105 to be distillate with anhydrous aluminum chlorid in solution in a part of the oil operated upon, it is to be understood that the distillation, which is primarily intended is one which is continued approximately to or 110 beyond the lowest point at which the residual material is sufficiently fluid for substantially the whole of it to be withdrawn from the still after the manner of a liquid, but that a distillation which is earlier arrested is not necessarily excluded, except in those claims where a distillation approximately to or beyond such point is specifically required by recital to that effect.

In stating in any claim that "liquid hydrocarbons and other matter" composing the 120 therein specified residual material are to be separated from each other, it is to be understood that said liquid hydrocarbons are primarily, but not necessarily exclusively, to be 125 obtained in a form which is practically free from aluminum chlorid.

The application for the present patent is a continuation of the application which was filed by me on April 25, 1914, and which 130

has been officially numbered 884,844. It is also an application under section 4897, Revised Statutes, for the invention or discovery which is set forth in the divisional 5 application that was filed by me on August 16, 1917, and was allowed October 6, 1917, the same being officially numbered 186,542. An application under said section 4897, Revised Statutes, for subject-matter of my said 10 divisional application was also filed by me on July 14, 1919, and has been officially numbered 310,875.

I claim herein as my invention or discovery:

- 15 1. The process of making low boiling oil from higher boiling petroleum, consisting in distilling petroleum in any appropriate form with anhydrous aluminum chlorid in solution in a part of the oil operated upon, 70 20 arresting the distillation while the residual material has a substantial content of liquid hydrocarbons, separating liquid hydrocarbons and other matter composing said residual material from each other, distilling 75 25 oil which is composed at least in part of so separated hydrocarbons, and subjecting part at least of the resulting distillate to distillation with anhydrous aluminum chlorid, substantially as described. 80 85 2. The process of making low boiling oil from higher boiling petroleum, consisting in distilling petroleum in any appropriate form with anhydrous aluminum chlorid in solution in a part of the oil operated upon, 90 95 arresting the distillation while the residual material has a substantial content of liquid hydrocarbons, washing part at least of the so obtained residual material with water in such manner that the washing water is applied to material which contains a large part 100 105 at least of the aluminum chlorid content of said residual material and which also has a substantial content of liquid hydrocarbons, distilling approximately at least to dryness oil which is composed at least in part of liquid hydrocarbons that have been separated from other matter by the washing, and subjecting a part at least of the resulting distillate to distillation with anhydrous aluminum chlorid, substantially as described. 110 115 3. The process of making low boiling oil and other products in making low boiling oil from higher boiling petroleum by the aid of anhydrous aluminum chlorid, consisting in distilling petroleum in any appropriate form with anhydrous aluminum chlorid in solution in a part of the oil operated upon, continuing such distillation at least until 120 125 the residual material approximates the lowest point at which it is sufficiently fluid to be withdrawn from the still after the manner of a liquid but not so far that the residual material ceases to have a substantial content of liquid hydrocarbons, arresting the distillation while the residual material has a substantial content of liquid hydrocarbons, and washing part at least of the so obtained residual material with water in such manner that the washing water is applied to material which contains a large part at least of the aluminum chlorid content of said residual material, substantially as described. 130
4. The process of making low boiling oil

from higher boiling petroleum, consisting in distilling petroleum in any appropriate form with anhydrous aluminum chlorid in solution in a part of the oil operated upon, arresting the distillation while the residual material has a substantial content of liquid hydrocarbons, washing part at least of the so obtained residual material with water in such manner that the washing water is applied to material which contains a large part at least of the aluminum chlorid content of said residual material and which also has a substantial content of liquid hydrocarbons, distilling oil which is composed at least in part of liquid hydrocarbons that have been separated from other matter by said washing, and subjecting a part at least of the resulting distillate to distillation with anhydrous aluminum chlorid, substantially as described.

5. The process of making low boiling oil from higher boiling petroleum, consisting in distilling petroleum in any appropriate form with anhydrous aluminum chlorid in solution in a part of the oil operated upon, 90 95 arresting the distillation while the residual material has a substantial content of liquid hydrocarbons, washing part at least of the so obtained residual material with water in such manner that the washing water is applied to material which contains a large part at least of the aluminum chlorid content of said residual material and which also has a substantial content of liquid hydrocarbons, distilling approximately at least to dryness oil which is composed at least in part of liquid hydrocarbons that have been separated from other matter by the washing, and subjecting a part at least of the resulting distillate to distillation with anhydrous aluminum chlorid, substantially as described.

6. The process of obtaining low boiling oil and other products in making low boiling oil from higher boiling petroleum by the aid of anhydrous aluminum chlorid, consisting in distilling petroleum in any appropriate form with anhydrous aluminum chlorid in solution in a part of the oil operated upon, continuing such distillation at least until the residual material approximates the lowest point at which it is sufficiently fluid to be withdrawn from the still after the manner of a liquid but not so far that the residual material ceases to have a substantial content of liquid hydrocarbons, arresting the distillation while the residual material has a substantial content of liquid hydrocarbons, and washing part at least of the so obtained residual material with water in such manner that the washing water is applied to material which contains a large part at least of the aluminum chlorid content of said residual material, substantially as described.

7. The process of obtaining low boiling

oil and other products in making low boiling oil from higher boiling petroleum by the aid of anhydrous aluminum chlorid, consisting in distilling petroleum in any appropriate form with anhydrous aluminum chlorid in solution in a part of the oil operated upon, continuing such distillation at least until the residual material approximates the lowest point at which it is sufficiently fluid to be withdrawn from the still after the manner of a liquid but not so far that the residual material ceases to be in condition to allow its carbonaceous content and the main part at least of its aluminum chlorid content to be separated from each other by washing with water, arresting the distillation while the residual material is in condition to allow its carbonaceous content and the main part at least of its aluminum chlorid content to be separated from each other by washing with water, and washing part at least of the so obtained residual material with water in such manner that the washing water is applied to material which contains a large part at least of the aluminum chlorid content of said residual material, substantially as described.

8. The process of obtaining low boiling oil and residual material of the hereinafter specified character in making low boiling oil from higher boiling petroleum by the aid of anhydrous aluminum chlorid consisting in distilling petroleum in any appropriate form with anhydrous aluminum chlorid in solution in a part of the oil operated upon, continuing such distillation at least until the residual material approximates the lowest point at which it can be freed from aluminum by boiling with water but not so far that the residual material ceases to be in condition to allow its carbonaceous content and the main part at least of its aluminum chlorid content to be separated from each other by washing with water, and arresting the distillation while the residual material is in condition to allow its carbonaceous content and the main part at least of its aluminum chlorid content to be separated from each other by washing with

50 water, substantially as described.

9. The process of obtaining low boiling oil and other products in making low boiling oil from higher boiling petroleum by the aid of anhydrous aluminum chlorid, consisting in distilling petroleum in any appropriate form with anhydrous aluminum chlorid in solution in a part of the oil operated upon, continuing such distillation at least until the residual material approximates the lowest point at which it can be freed from aluminum by boiling with water, but not so far that the residual material ceases to be in condition to allow its carbonaceous content and the main part at least of its aluminum chlorid content to be separated from

each other by washing with water, arresting the distillation while the residual material is in condition to allow its carbonaceous content and the main part at least of its aluminum chlorid content to be separated from each other by washing with water, and separating the aluminum chlorid and the carbonaceous matter in said residual material in part at least from each other, substantially as described.

10. The process of obtaining low boiling oil and other products in making low boiling oil from higher boiling petroleum by the aid of anhydrous chlorid, consisting in distilling petroleum in any appropriate form with anhydrous chlorid in solution in a part of the oil operated upon, continuing such distillation at least until the residual material approximates the lowest point at which it can be freed from aluminum by boiling with water but not so far that the residual material ceases to be in condition to allow its carbonaceous content and the main part at least of its aluminum chlorid content to be separated from each other by washing with water, arresting the distillation while the residual material is in condition to allow its carbonaceous content and the main part at least of its aluminum chlorid content to be separated from each other by washing with water, and washing part at least of the so obtained residual material with water in such manner that the washing water is applied to material which contains a large part at least of the aluminum chlorid content of said residual material, substantially as described.

11. The process of obtaining low boiling oil and other products in making low boiling oil from higher boiling petroleum by the aid of anhydrous aluminum chlorid, consisting in distilling petroleum in any appropriate form with a limited proportion, not more than about ten per cent. by weight, of anhydrous aluminum chlorid in solution in a part of the oil operated upon, conducting the distillation with such regulation of the fires as to maintain a good flow of distillate from the condenser outlet by reason of the rising temperature of the oil operated upon, arresting the distillation while the residual material is in condition to allow its carbonaceous content and the main part at least of the aluminum chlorid content to be separated from each other by washing with water, and washing part at least of the so obtained residual material with water in such manner that the washing water is applied to material which contains a large part at least of the aluminum chlorid content of said residual material, substantially as described.

12. The process of obtaining low boiling oil and other products in making low boiling oil from higher boiling petroleum by the

aid of anhydrous aluminum chlorid, consisting in distilling petroleum in any appropriate form with a limited proportion, not more than about ten per cent. by weight, of 5 anhydrous aluminum chlorid in solution in a part of the oil operated upon, conducting the distillation with such regulation of the fires as to maintain a good flow of distillate from the condenser outlet by reason of the 10 rising temperature of the oil operated upon, continuing the distillation with rising temperature in said oil at least until the residual material approximates the lowest point at which it can be freed from aluminum by 15 boiling with water but not so far that the residual material ceases to be in condition to allow its carbonaceous content and the main part at least of its aluminum chlorid

content to be separated from each other by washing with water, arresting the distillation while the residual material is in condition to allow its carbonaceous content and the main part at least of the aluminum chlorid content to be separated from each other by washing with water, and washing 20 part at least of the so obtained residual material with water in such manner that the washing water is applied to material which contains a large part at least of the aluminum chlorid content of said residual material, substantially as described. 25

In testimony whereof I affix my signature to the foregoing specification, at Bayonne, N. J., this seventeenth day of September, 1919.

ERNEST B. COBB.

It is hereby certified that in Letters Patent No. 1,322,762, granted November 25, 1919, upon the application of Ernest B. Cobb, of Jersey City, New Jersey, for an improvement in "Making Low-Boiling Oil from Higher-Boiling Petroleum or Related Oil," errors appear in the printed specification requiring correction as follows: Page 6, line 106, for the word "distillate" read *distilled*; page 8, lines 79 and 81, claim 10, after the word "anhydrous" insert the word *aluminum*; and that the said Letters Patent should be read with these corrections therein that the same may conform to the record of the case in the Patent Office.

Signed and sealed this 30th day of December, A. D., 1919.

[SEAL.]

M. H. COULSTON,

Acting Commissioner of Patents.

Cl. 196—26.
